BEARING RELINING CAP

Filed August 2, 1923

Fig. 1.

Fig. 2.

Fig. 3.

Fig. 4.

A technical drawing of a mechanical assembly, likely a cylinder or piston rod. The drawing shows a central vertical rod with a flared top and bottom. The top section is labeled with numbers 12, 3, 2, 1, 5, 6, 11, 7, 17, 16, 15, 13, 8, 13, 16, 5, and 12. The bottom section is labeled with numbers 9, 11, 1, 12, 3, 5, 6, 7, 11, 17, and 16. The drawing is labeled 'Fig. 5.' in the upper right corner and 'By' in the lower right corner.

Attorney

UNITED STATES PATENT OFFICE.

LYMAN E. SHIPLEY, OF CARLTON, OREGON.

BEARING-RELINING CAP.

Application filed August 2, 1923. Serial No. 655,282.

To all whom it may concern:

Be it known that I, LYMAN E. SHIPLEY, a citizen of the United States, residing at Carlton, in the county of Yamhill, State of Oregon, have invented certain new and useful Improvements in Bearing-Relining Caps, of which the following is a specification.

This invention relates to devices adapted to hold a shaft while the bearing is being relined, and has for its objects to provide a temporary or removable gage against which the shaft may be held to bring it to proper alignment whereby, when it is so aligned, the molten metal for the bearing may be poured around it; to provide means for clamping the shaft in aligned position; and to provide a passage through which the molten metal may reach the bearing. Another object is to provide such a device which is always available so that a bearing may be relined whenever required. Other objects are to provide a device which will save time and expense in relining a bearing and which is cheap to make, easy to apply and accurate in results.

I attain these and other objects by the devices, mechanisms and arrangements illustrated in the accompanying drawings, in which—

Fig. 1 is a cross-section of a bearing fitted with my cap and being relined; Figs. 2 and 3 are a plan and side elevation thereof, respectively; Fig. 4 is an end elevation to illustrate the shaft clamp; and Fig. 5 is a plan of another form of my invention.

Similar numerals of reference refer to similar parts throughout the several views.

The operation of relining a shaft bearing is, at the present time, long and expensive. The greater part of the time spent is devoted to properly aligning the shaft before the bearing metal is poured. My invention is intended to reduce the time spent in this operation by providing a permanent gage for a bearing to which the shaft is brought and, when the shaft is in tight engagement with this gage, it is in proper alignment therein. This gage is removable from the bearing but when fastened in place always occupies the same position therein.

Referring to the drawings the bearing frame 1 is provided with a cylindrical bearing groove or chamber 2 into which the bearing metal is poured, a separation surface 3 positioned at the diameter of the

shaft 4, and a shoulder 5, at right angles to the surface 3 and extending outward therefrom to the outer surface 6 of the frame. The surfaces 5 and 6 are finished smooth. The ordinary service cap (not shown) is attached to the frame by four studs 7 and it fits closely between the shoulders 5. When it is desired to reline the bearing groove 2, the service cap is removed and the gage plate or relining cap 8 is substituted therefor. This cap is illustrated in the drawings and fits tightly on both surfaces 5 and 6 and its shaft gage groove 9 fits the shaft 4. Therefore, if the said cap 8 is brought tightly into this predetermined position, and the shaft 4 is brought tightly into its gage groove 9 therein, the said shaft will then be in its predetermined or aligned, position. The cap 8 is provided with a portion 10 extending about to the surface 3 of the frame and fitting snugly between the shoulders 5, and also with lateral securing flanges 11 through which the studs 7 pass into the screw-threaded holes 12 in the frame, said flanges 11 being screwed tightly against the surfaces 6 thereby.

I have illustrated two forms of my cap. The form illustrated in Fig. 5 covers only a portion of the bearing and leaves a part thereof uncovered. The molten metal may be poured directly into the groove 2 beside the bearing cap. In practice the ends of the groove 2, outside of the bearing, are stopped with a suitable plastic dam 13, such as clay, which prevents the molten bearing metal from running out at the ends of the groove. In the form of my cap illustrated in Figs. 1, 2 and 3 the cap covers the entire bearing and I provide a pouring passage 14 there-through, through which a stream of molten metal may be poured into the groove 2, as shown in Fig. 1.

In some cases the shaft 4 may be supported in said aligned position by means of a clamp yoke 15, hung by two bolts 16 from two end lugs 17 extending from one end of the cap. The yoke 15 passes under the shaft 4 and, when the nuts on the bolts 16 are screwed down thereon, draws it tightly into the groove 9 into aligned position. In other cases special attachments may be used to hold the shaft when the bearing is being poured.

This bearing relining cap is not intended to be used as a part of the shaft bearing and is to be removed from the bearing as soon

as its function has been fulfilled, and therefore it has no wear and always assumes the same position whenever attached to the bearing. Since the shaft itself does not wear any substantial amount it is evident that the central axis of the shaft also comes to gage when the apparatus is set as above.

Having, therefore, described my invention what I claim is:—

- 10 1. In a bearing relining device, a gage plate adapted to be secured to the bearing frame in predetermined position, and having a shaft gage groove therein wherein, when the shaft is drawn tight, it is brought to predetermined gage position and is separated from that portion of the bearing lying in the bearing frame, and providing a space through which molten bearing metal may be poured to fill the space thus formed
- 15 2. In the device of claim 1, between the shaft and the bearing lying in the bearing frame, whereby said metal, when cooled, forms an aligned and gaged bearing for the shaft in the bearing frame; in com-

bination with means attached to and extending laterally from said gage plate and 25 engaging the shaft to one side of the bearing and adapted to draw the shaft into said gage position and to support it therein while the bearing is being thus formed.

2. A bearing relining device as set forth in claim 1, wherein said shaft supporting means comprises a yoke, adjustably suspended from said gage plate, and adapted to support the shaft and to draw it into gage 30 position.

3. A bearing relining device as set forth in claim 1, wherein said shaft supporting means comprises a pair of lugs extending laterally from said gage plate; a yoke adapted to pass under the shaft to one side of the 40 bearing; and bolts, passing through said lugs and said yoke, whereby the yoke and shaft may be supported and drawn up into gage position.

LYMAN E. SHIPLEY.
